UNITED STATES PATENT OFFICE.

CHARLES CRISMAN, OF WATERVILLE, MAINE.

AUTOSLED.

SPECIFICATION forming part of Letters Patent No. 766,672, dated August 2, 1904.

Application filed March 31, 1904. Serial No. 200,986. (No model.)

To all whom it may concern:

Be it known that I, CHARLES CRISMAN, a citizen of the United States, residing at Waterville, in the county of Kennebec and State of Maine, have invented new and useful Improvements in Autosleds, of which the following is a specification.

My invention relates to new and useful improvements in propelling mechanism for sleds and like vehicles; and its object is to provide means whereby the vehicle can be propelled over ice or snow by any suitable motor which may be placed thereon.

The invention consists of transversely-extending shafts which are supported from bell-crank levers having means for moving them upon their fulcrums. Secured to the ends of each of the shafts are sprocket-wheels, and arranged on these wheels and close to each of the runners of the sled are chains having projections adapted to engage the ice or snow. Means are provided for transmitting rotary motion from a suitable motor to one of the shafts.

The invention also consists of the further novel construction and combination of parts hereinafter more fully described and claimed, and illustrated in the accompanying drawings, showing the preferred form of my invention, and in which—

Figure 1 is a plan view of the running-gear of my improved sled, portions of some of the cross-beams thereof being removed; and Fig. 2 is a section on line 2 2, Fig. 1.

Referring to the figures by numerals of reference, 1 is the body of the sled, and the same is supported by springs 2 and 3 upon trucks 4 and 5, respectively. The truck 4 is so connected to the body as to be readily swung laterally, so as to guide the sled, whereas the truck 5 is incapable of lateral movement independently of the body. Extending longitudinally of the center of truck 5 is a beam 6, to which are fulcrumed bell-crank levers 7, and these levers are connected by a rod 8, which is connected to one end of a lever 9 by means of a link 10. This lever is fulcrumed upon the body 1 and is provided with any suitable means, as a toothed segment 11, for locking it in adjusted position. Depending from

each bell-crank lever 7 is a link 12, and these links are connected to transversely-extending shafts 13 and 14, which are arranged adjacent the rear and front ends of truck 5. The end portions of the shaft 14 are supported by rods 55 15, which are pivoted to the body 1 adjacent springs 3, and secured to the ends of the shafts 13 and 14 are sprocket-wheels 16, the peripheries of which normally overlap the runners of the truck 5. These sprocket-wheels are arranged close to the inner faces of the runners and have chains 17 mounted on them, and projecting outwardly from the chains are prongs 18, adapted to engage the ice or snow. A small sprocket-wheel 19 is 65 connected to the central portion of shaft 14 and is adapted to be rotated by a chain 20, extending from a suitable motor 21 upon the body 1.

When it is desired to propel the sled, motion 70 is transmitted to sprocket 19 from motor 21, and the shaft 14 and sprocket 16 will thus be rotated and will cause the chains 17 to rotate the rear sprocket 16 and the shaft 13. By swinging the lever 9 in one direction the bell-crank lever 7 will press the shafts 13 and 14 downward, and thus bring the moving chain 17 below the working faces of the runners to truck 5, and the projections 18 will thus be caused to engage the snow or ice and the sled 75 will be moved forward. When it is desired to stop the sled, the lever 9 is swung in such a direction as to cause the bell-crank levers 7 to raise the shafts 13 and 14. It will be seen that this mechanism is extremely simple in 80 construction and can be readily attached to a sled and easily manipulated.

In the foregoing description I have shown the preferred form of my invention; but I do not limit myself thereto, as I am aware that 90 modifications may be made therein without departing from the spirit or sacrificing any of the advantages thereof, and I therefore reserve the right to make such changes as fairly fall within the scope of my invention.

Having thus fully described the invention, what is claimed as new is—

1. In a device of the character described, the combination with a truck having a body supported thereon, of transversely-extending 100

shafts, sprockets thereon, chains mounted upon the sprockets and parallel with the sides of the truck, projections upon the chains, bell-crank levers connected to the truck, link connections between said levers and the shafts, means for simultaneously operating the levers, and power mechanism connected to one of the shafts.

2. In a device of the character described, the combination with a truck and a body supported thereon; of shafts extending transversely of the truck, sprockets thereon, chains connecting the sprockets and parallel with the sides of the truck, projections upon the chains,

bell-crank levers pivoted to the truck, links 15 connecting the levers with the shafts, an operating-lever, a rigid connection between the bell-crank levers, a link connecting said levers with the operating-lever, brace-rods pivoted to the body and engaging one of the shafts, 20 and means for rotating the shafts.

In testimony whereof I affix my signature in presence of two witnesses.

CHARLES CRISMAN.
